UNITED STATES PATENT OFFICE.

NELSON CURTIS, OF BOSTON, MASSACHUSETTS.

PRESSURE-REGULATOR.

SPECIFICATION forming part of Letters Patent No. 500,994, dated July 4, 1893.

Application filed August 18, 1888. Serial No. 283,059. (No model.)

To all whom it may concern:

Be it known that I, NELSON CURTIS, of Boston, Massachusetts, have invented an Improvement in Pressure-Regulators, of which 5 the following is a specification.

The invention relates to that class of pressure regulators in which the pressure of the fluid operating a mechanism of the system to which the regulator is applied, is controlled 10 by the pressure of a separate or independent fluid; and as in regulators of this class heretofore in use the instrument embraces two valves, one a balanced piston valve in the main passageway of the operating fluid, and the 15 other, an auxiliary valve in a relief passageway from the high pressure side of the said main passageway, which said auxiliary valve is operated in one direction by a spring and in the other by the pressure of the said separate and independent fluid.

The invention consists in a detail of construction, the principal feature of which, as hereinafter set forth is a hook by the use of which the usual directions of the two said 25 counteracting forces controlling the said auxiliary valve, that is, the force of the said spring and the force of said independent fluid, are reversed; whereby in a compact instrument affording great facility for assembling and 30 adjusting the parts, the said operating and the said independent fluids are kept well apart.

As in former pressure regulators used by me, and as in steam traps, and other fluid systems heretofore in use, I employ in carrying out the present invention, a piston valve located in the main passage way of the working fluid, and an auxiliary or controlling valve in a small passage way which connects 40 the two parts of the said main passage way that lie on either side of the port of the said piston valve.

In the drawings, Figure 1 is a vertical elevation of the said improved pump regulator. 45 Fig. 2 is a vertical sectional elevation of the same.

A is a shell or casting provided with hollow horizontal arms B B' and an upright chamber C between said arms, the said two arms 50 and chamber forming a main passage-way for steam or other fluid.

D is the piston valve in said main passage-

way having a seat a supported by interior flanges or walls of the shell. The upper part of the piston valve is cup-shaped as shown, 55 and fits loosely in a cylinder b screwed into the walls of the chamber C from the top.

E is a hollow piece screwed into the top of the cylinder b and containing the port c of the auxiliary valve F whose stem works tightly 60 through a guide piece d screwed into the piece E, as shown.

G is a conical shaped hollow casting bolted as shown to the top of the shell A. It is slotted, as shown, to form a free air space for the 65 purpose hereinafter set forth and to receive the point of the hook H which takes into the stem of the auxiliary valve F, as shown; and it supports on its top a diaphragm g that also rests on the flanged top of the stem of the 70 auxiliary valve F. This diaphragm is held in place by a cap or casting e screwed upon the top of the casting G to form a tight chamber J above the diaphragm.

The cap e carries an upright projection 75 serving as a support and guide for the hook or arm H and its operating mechanism. This projection passes, as shown, loosely through a coiled spring S in a hole in the upper end of the hook or arm H, and also loosely through 80 a handle piece K that screws into said hole in said arm H to compress the said spring S more or less, the office of the spring S being to lift the auxiliary valve F against any pressure there may be above the diaphragm g. 85

L is a union pipe screwed into cap e to serve as the continuation of an inlet passageway to chamber J above the diaphragm from the fluid raised by the pump.

The shell A has within one of its walls a 90 passage N opening into arm B' and communicating with the interior of hollow piece E, which communicates by port c with the cup of the piston valve D, which by the loose fit of the piston has communication with arm B, 95 thus forming the small passage-way for the main fluid hereinbefore mentioned.

A spring, S', helps the piston valve D to its seat when the port c is closed as aforesaid.

In this pressure regulator there is no communication between the fluids of the two systems. Moreover air circulating freely within the hollow casing G separates the operating fluid in the lower part of the regulator from

the fluid in the chamber J (this being a portion of the fluid raised by the pump) so that the temperature of the fluid in said chamber J is not injuriously affected by that of the operating fluid. If the temperature of the fluid in chamber J were abnormally raised its expansive force or pressure would tend to interfere with the proper movement of the diaphragm. In operation when the pressure of the independent fluid above the said diaphragm *g*, is less than that of spring S, the auxiliary valve will be lifted from its seat. The smaller passage way for the main fluid is then opened relieving the pressure above the piston of the main valve in the main fluid passageway and allowing that valve to open and admit a fresh supply of working fluid.

I claim—

1. The combination with a main passage-way for fluid under pressure, a piston valve therein, a relief passageway leading out of said main passageway on the high pressure side of said piston valve, and an auxiliary valve in said relief passageway, all within

shell A, substantially as described, of fluid 25 chamber J, supported by said shell A, and provided with said flexible side or diaphragm *g*, in contact with the free end of the stem of said auxiliary valve, spring S, and hook H, taking into said stem, substantially as de- 30 scribed.

2. The combination with a main passage-way for fluid under pressure, a piston-valve therein, a smaller passage-way connecting two parts of the said main passage-way, one above 35 and the other below the port of said piston-valve and an auxiliary valve in said smaller passage-way, all within shell A, substantially as described, of fluid chamber J, supported by said shell A and provided with said flexible side or diaphragm *g* in contact with the free end of stem of auxiliary valve, hook H taking into said stem and spring S, substantially as described.

NELSON CURTIS.
